UNITED STATES PATENT OFFICE.

MILTON S. JOHNSON, OF YORK, PENNSYLVANIA.

GRINDING-MILL.

SPECIFICATION forming part of Letters Patent No. 795,133, dated July 18, 1905.

Application filed August 21, 1901. Serial No. 72,787.

To all whom it may concern:

Be it known that I, MILTON S. JOHNSON, a citizen of the United States, residing at York, in the county of York and State of Pennsylvania, have invented certain new and useful Improvements in Grinding-Mills; and I do declare the following to be a full, clear, and exact description of the invention, such as will enable others skilled in the art to which it applies to make and use the same, reference being had to the accompanying drawings, and to the figures of reference marked thereon, which form a part of this specification.

My invention relates to a machine for grinding materials for various purposes, and is particularly well adapted for grinding into fine particles materials used in the manufacture of explosive powders, although it may be used for other purposes.

The invention has for its object to provide a machine in which the material will be reduced or ground into fine particles by a number of beaters arranged as hereinafter described in a cylinder, the strong circulation of air being maintained in said cylinder, so as to expeditiously dry the material during the grinding operation, the degree of fineness to which the material may be reduced being regulated by certain valves arranged as hereinafter specified whereby the material may be held within the grinding-cylinder a longer or shorter period of time, according to the degree of fineness to which the material is to be reduced.

The invention has also for its object to simplify the construction of such a machine and to provide a construction in which the strain upon the parts will be reduced to the minimum and in which increased efficiency is obtained.

To the accomplishment of the foregoing and such other objects as may hereinafter appear, the invention consists in the construction and in the combination of parts hereinafter particularly described and then sought to be clearly defined by the claims, reference being had to the accompanying drawings, forming a part hereof, and in which—

Figure 1 is a plan view of the machine; Fig. 2, a side elevation, partly in section; Fig. 3, a sectional detail showing application of the

slide-valves. Fig. 4 is a vertical section on line 44 of Fig. 2. Fig. 5 is a transverse section on line 55 of Fig. 2. Fig. 6 is a front elevation of one set of beaters, showing one arm with the beater removed. Fig. 7 is a side view of one set of beaters with certain parts detached, and Fig. 8 is a transverse section on line 88 of Fig. 2.

In the drawings the numeral 1 designates a bed-plate formed with suitable boxings 2, in which is journaled the driving-shaft 3, provided with the driving-pulleys 4, located at opposite sides of the grinding-cylinder 5, the lower portion or half of said cylinder being cast with the bed 1 or otherwise may be made as a part thereof, and the boxings 2 may be provided with oil-cups 6. The upper portion or half of the cylinder 5 is made separate from the lower part, and the two parts are held together by means of bolts 7, passed through flanges 8, projecting from the two parts of the cylinder. The interior of the cylinder is lined with steel or other hardened plates 9, of which two are illustrated—one fitting in the lower half and the other in the upper half of the cylinder, the meeting edges of the plate being provided with overlapping shoulders 10, as illustrated in Fig. 5 of the drawings, and the exposed faces of the plates are formed with a corrugated or undulating surface 11, so as to cooperate with the beaters hereinafter described for grinding or comminuting the material being reduced.

The beaters are formed of a number of arms 12, extending radially from the shaft 3 and provided with detachable blades 13. The blades are formed with shanks 14, which bear against the rear of the arms 12, the arms being formed with a reduced portion 15 to receive the shanks of the blades, said shanks being formed each with a lug or shoulder 16, which fits in a depression 17, formed in the arm, so as to prevent outward longitudinal movement of the blade on its arm, and the ends of the arms are each formed with a dovetailed tongue 17^a to fit in a correspondingly-shaped groove 17^b in the edge of the beater, so as to assist in holding the parts together. The blades are secured to the arms by means

of rings or collars 18, which encircle the arm and the shank portion of the blades and which are provided with set-screws 19, by which to tighten the collars, and thus securely clamp 5 the blades to the radiating arms. Any desired number of these beaters are employed, and they will be so arranged within the cylinder 5 as to extend in lines forming a spiral from the receiving end of the cylinder toward 10 the discharge end, so as to facilitate the movement or feed of the material through the cylinder. By attaching the blades to the beater-arms in the manner indicated they can be readily removed and replaced by a new one or by 15 a beater of a different form, according to the character of the material to be reduced and the action desired thereon.

For the purpose of creating an air-blast through the grinding-cylinder 5, so as to dry 20 the material and at the same time impel it into the receptacle or receiving-room for the ground material, I locate a partition 20 inside of the cylinder, near the discharge end thereof, so as to form a compartment 21, in which 25 will be located a fan composed of the arms 22, extending from a hub 23, which will be bolted to the shaft 3, said arms 22 having the fan-blades 24. A spout 25 leads from the fan-chamber and will discharge into the receiving- 30 room for the ground material. The adjacent ends of the partition 20 next to the shaft 3 have a portion removed, so as to form an opening 26 for the passage of the material from the grinding-cylinder into the fan-chamber. 35 For the purpose of varying the size of this opening, so as to increase or lessen the speed of discharge from the grinding-cylinder into the feed-chamber, and thus regulate the degree of fineness to which the material is to be 40 ground by holding it a longer or a shorter period within the grinding-cylinder, I provide two slide-valves 27 and 28, one above and the other below the shaft 3, which valves are adapted to be moved toward and from each 45 other across the opening 26 in the partition 20, so as to regulate the size of the opening by the adjustment of these valves. The valves are operated by means of a threaded rod or screw 29, which is formed with right-hand 50 threads 30 for a portion of its length and with left-hand threads 31 for another portion of its length, which portion may be reduced in diameter, as illustrated in Fig. 3 of the drawings, said rod passing through a suitable bearing 32 on the grinding-cylinder and having its right-hand threaded portion engaging a threaded nut 33 on the slide 27 and its left-hand threaded portion engaging a threaded nut 34, formed on or as a part of a 55 yoke 35, which straddles the shaft 3 and is secured to the slide 28. By turning the rod or screw 29 in one direction the two slide-valves are drawn toward each other, so as to reduce the size of the exit-opening 26 in the 60 partition 20, and by turning the rod in the 65

opposite direction the slide-valves are separated and the exit-opening thus enlarged. In this manner the exit of the material from the grinding-cylinder into the fan-chamber can be regulated and controlled to a nicety and 70 the degree of fineness to which the material is to be reduced can be regulated within quite large limits. The partition 20 will be recessed for a portion of its length from the top downwardly, so that the operating-rod 29, carrying the nuts of the slide-valve, may work within said recess. 75

The material to be ground is received into the cylinder 5 from a feed-hopper 36, the opening between which and the cylinder is 80 controlled by slide-valve 37, which is raised and lowered by a hand-wheel 38, engaging the threaded portion of a rod 39, extending from the slide-valve 37 and through a suitable bearing 40 at the top of the cylinder 5, 85 the other slide-valve-operating rod 29 being operated by a hand-wheel 41.

The material to be reduced in the grinding-cylinder 5 is subjected to a preliminary reduction before entering the inlet feed-hopper 90 36 to the grinding-cylinder, which preliminary reduction is effected by means which I shall now describe.

The numeral 42 designates two standards suitably bolted to the bed-plate 1 and which 95 may be connected together by the brace-rods 43. These standards support two crushing-rolls 44 and 45, which may have a smooth surface, as indicated by the roll 44, or a roughened or toothed surface, as indicated by the roll 45. The journals of the roll 45 fit in boxes 46, which are held in a stationary position in the ways 47, formed in the tops of the standards 42, by means of bolts 48, while the journals of the rolls 44 fit in boxes 49, 100 adapted to slide in the ways 47 in the tops of the standards 42, said sliding boxes being each under the influence of a coiled spring 50, which at one end fits around a stud 51, projecting from the box 49, and at the other end 105 fitting around a stud 52, projecting from a sliding block 53, which is moved back and forth by a screw 54, swiveled in the end of the standard 42 and provided with a hand-wheel 55, so that by compressing said springs 110 by the screws, operating as specified, the roll mounted in the sliding boxes will be pressed against the other roll with more or less pressure, according to the tension placed upon the springs, and thus regulate the crushing pressure exerted by the two rolls upon the material thus subjected to a preliminary reduction. The material is fed to the crushing-rolls from a hopper 56, which is formed with flanges 57, by which and the bolts 58 the hopper is secured to the top of the standards 42, the walls of the hopper converging inwardly, and the two rolls filling the discharge-opening in the bottom of the hopper, the side walls of the hopper fitting quite closely to the sur- 115 120 125 130

face of the rolls and the end walls overlapping the ends of the rolls.

The numerals 59 designate caps which encircle the journals of both rolls on both sides 5 of each of the standards 42, and thus serve as a housing to protect the journals at those points.

The material crushed by the rolls 44 and 45 falls into a trough 60, which delivers it 10 into the hopper 36 of the grinding-cylinder 5. This trough is adapted to oscillate, and it inclines from its rear to its forward end. The rear end of the trough is formed with an extension 61, through which passes a pintle 62, 15 extending from the under side of the top portion of the rear standard 42, so that the trough may turn upon the pintle as a pivot, a pin 63, passed through the pintle, and a washer 64, interposed between said pin and the extension 20 61, serving to hold the trough to the pintle. The trough at its forward end is suspended by means of a link 66, supported by the extension of one of the brace-rods 43 and having its lower end connected by a pin 67 to a 25 bar 68, extending from the side of the trough next thereto, and by a rocking arm 69, fulcrumed upon the end of the other brace-rod 43, extending from the other side of the standard 42 and having its lower end connected to 30 the bar 68 by a pin 70. The upper member of the rocking arm 69 is connected by a pin 71 to the eccentric-arm 72, which at its inner end has a collar 73 fitting around an eccentric pin 74 on the end of the journal of the crushing-roll 45, the collar 73 of the eccentric-arm being formed in two parts, which are bolted 35 together by bolts 75 passing through flanges 76, projecting from the two parts of the collar, the outer end of arm 72 being held to the pin 71 by means of a washer 77 and nut 78. Under this construction the trough 60 is vibrated sidewise by means of the rocking arm 69, actuated by the eccentric mounted upon the journal of one of the crushing-rolls, and 40 thus a constant and regular feed of material from the crushing-rolls to the feed-hopper of the grinding-cylinder is effected through the medium of the vibrating trough, which delivers the material from the crushing-rolls to 45 the feed-hopper.

The crushing-roll 45 has a gear-wheel 79 mounted on its journal, which extends beyond the outer standard 42, and this wheel derives its motion from a toothed pinion 81 on the 50 driving-shaft 3. It will thus be seen that the beaters in the grinding-cylinder 5 and the crushing-rolls are actuated from the same driving-shaft and that the trough beneath the crushing-rolls receives its vibration from 55 connections with one of the crushing-rolls, and thus there is a concert of action between the beaters of the grinding-cylinder and the crushing-rolls in reducing the material to the condition desired, as well as a concert of action 60 with the trough which delivers the prelimi-

narily-reduced material to the beaters of the grinding-cylinder for a further reduction.

I have illustrated and described with particularity the preferred details of construction and arrangement of the several parts; 70 but it is obvious that there can be changes made in the details of some of the parts and essential features of my invention still be retained.

Having described my invention and set 75 forth its merits, what I claim is—

1. In a grinding-mill, the combination with a cylinder divided by a partition into a grinding-compartment and a fan-compartment, said partition having an opening formed in it for 80 the passage of material from the grinding-compartment into the fan-compartment, a shaft passing centrally through said cylinder and provided within the grinding-compartment with a series of beaters and with fan-blades within the fan-compartment, slide-valves for varying the size of the opening in the partition, said valves fitting one above and the other below the shaft and adapted to be moved toward and away from each other, and 85 means for moving said valves toward and from each other, substantially as described.

2. In a grinding-mill, the combination with a cylinder divided by a partition into a grinding-compartment and a fan-compartment, said 90 partition having an opening for the passage of material from the grinding-compartment into the fan-compartment, slide-valves for varying the size of the opening in the partition, a threaded rod provided with right and left 95 hand threads in engagement with parts of the slide-valves for moving said valves toward and from each other, and a shaft passing centrally through the cylinder and provided within the grinding-compartment with a series of beaters and within the fan-compartment with fan-blades, substantially as described.

3. In a grinding-mill, the combination of a cylinder formed with a grinding-compartment, a rotatable shaft passed centrally 110 through the cylinder, a series of beaters secured to said shaft, a vibrating trough for feeding material to the cylinder, and means for vibrating the trough, said means comprising a rocker-arm connected to the trough, an eccentric operatively connected with said arm, and a rotatable member connecting the eccentric with the shaft which carries the beaters 115 so as to derive motion from said shaft, substantially as described.

4. In a grinding-mill, the combination with the cylinder formed with a grinding-compartment, of a shaft passed centrally through said cylinder and provided within the grinding-compartment with beaters, said beaters consisting of arms extending from the shaft and removable blades formed with shanks clamped to said arms by rings encircling the arms and shanks and secured by set-screws, substantially as described.

5. In a grinding-mill, the combination with a grinding-cylinder formed with a feed-hopper, of crushing-rolls for effecting a preliminary reduction of the material, an oscillatory trough intermediate of the crushing-rolls and grinding-cylinder and receiving the material from the crushing-rolls and delivering it to the feed-hopper of the grinding-cylinder, said trough being pivoted at one end so as to swing laterally, a rocking arm connected with the opposite end of said oscillatory trough, and an eccentric-rod connecting the rocking arm with one of the crushing-rolls for transmitting motion from said roll to the oscillatory trough, substantially as described.

6. In a grinding-mill, the combination with the grinding-cylinder and the trough for feeding material thereto, of a set of preliminary-reducing crushing-rolls, one of said rolls being mounted in sliding boxes, sliding blocks opposite to and spaced from said boxes, springs fitting in the spaces between the boxes and blocks and acting upon said boxes, and screws connected with the sliding blocks for varying

the tension of said springs, substantially as described.

7. A grinding-mill comprising a cylinder provided with beaters, a drive-shaft for the same, crushing-rolls, means connecting said rolls with the drive-shaft of the beaters to derive motion therefrom, an oscillatory trough for delivering the material from the crushing-rolls to the grinding-cylinder, said trough being pivoted at one end so as to have a lateral swing, a rocking arm and a swinging link connected with the trough to support the same at the end next to the grinding-cylinder, and an eccentric mounted on the journal of one of the crushing-rolls and connected with one end of the rocking arm for transmitting an oscillatory movement to the trough from said crushing-roll, substantially as described.

In testimony whereof I affix my signature in presence of two witnesses.

MILTON S. JOHNSON.
